Patented Feb. 22, 1916.

UNITED STATES PATENT OFFICE.

WILLIAM R. TAYLOR, OF RACINE, WISCONSIN.

DETACHABLE HINGE.

1,172,500.

Specification of Letters Patent.

Patented Feb. 22, 1916.

Application filed October 20, 1915. Serial No. 56,828.

To all whom it may concern:

Be it known that I, WILLIAM R. TAYLOR, a citizen of the United States, and resident of Racine, in the county of Racine and State of Wisconsin, have invented new and useful Improvements in Detachable Hinges, of which the following is a description, reference being had to the accompanying drawings, which are a part of this specification.

10 This invention has for its object to provide a spring hinge for screen doors or storm doors or the like which will permit of the door being quickly disconnected without the removal of screws or hinge pins or other securing devices by providing means for locking the hinge plates with relation to each other to take the pressure of the spring from them and permit the connecting plate to be disconnected from the hinge.

15 This invention further has for its object to overcome certain difficulties which attend the manufacture and use of the detachable hinge covered by Patent No. 1,057,960 to 25 Heeter and Kline, dated April 1, 1913.

20 One object of the invention is to avoid a binding clamping action between the separate member or connecting plate and the hinge leaf engaged with it when attempting 30 to disconnect them, but to so construct these interlocking parts that they may freely swing out of connection with each other when the spring tension is taken off of the hinge even though in doing so the door is 35 swung open to its full limit.

Another object of the invention is to so construct the hinge parts of sheet metal as to utilize substantially the full length of the hinge pin as a support for the coil 40 spring and thereby permit the use of a spring of maximum length.

Another object of the invention is to inclose the spring within a housing formed by one of the hinge leaves to hide it from 45 view and protect it from engagement with clothing especially in case of the spring becoming broken.

50 Another object of the invention is to provide such a hinge with hinge leaves provided with end flanges in face to face contact with each other and having the hinge pin passing therethrough and also having registering openings adapted to receive a locking

pin for locking the hinge leaves together in their folded position, as when the door is 55 removed, the separate member or connecting plate having similar end flanges and openings registering with the openings of the hinge leaf with which it connects to receive the locking pin for locking the connecting 60 plate to the hinge in case the spring becomes broken.

Another object of the invention is to provide the hinge pin with loose bearing sleeves near its ends to prevent the spring 65 contacting therewith.

Another object of the invention is to improve various details of construction to add strength and durability and convenience of operation thereto.

With the above and other objects in view the invention consists in the detachable hinge as herein claimed and all equivalents.

Referring to the accompanying drawings, 70 in which like characters of reference indicate the same parts in the different views, Figure 1 is a front view of a detachable hinge constructed in accordance with this invention and applied to a door, the parts being in section; Fig. 2 is a plan view 75 thereof; Fig. 3 is a sectional plan view thereof with the door open and the bail loop engaged with the catch ready for permitting the door to be detached; Fig. 4 is a plan view thereof with the door and its connecting 80 plate shown in dotted lines; Fig. 5 is a front view of the hinge with the door and its connecting plate detached therefrom; Fig. 6 is a detail view showing the locking 85 pin in position for locking the connecting plate with the hinge; and, Fig. 7 is a detail view showing a modification.

In these drawings the detachable hinge of this invention is shown as consisting of hinge leaves or plates 10 and 11 having end 90 flanges 12 which project beyond the inner edges of said plates and fit together face to face and have a pivot pin 13 loosely passing therethrough. The end flanges 12 of the hinge plate 10 fit against the inner faces of 100 the end flanges of the hinge plate 11 and between them the sheet metal of which the hinge plate 10 is formed is bent up and around to form a somewhat cylindrical spring housing 14 which is open in the rear, 105 A coil spring 15 is fitted within the spring

housing 14 around the pivot pin 13 and one straight end thereof passes through an opening in the spring housing and bears against the face of the hinge plate 10 while the other end thereof passes through a slot 16 of the spring housing and bears against the face of the hinge plate 11. Loose bearing sleeves 17 surround the pivot pin 13 with flaring ends engaging the ends of the coil spring, and these sleeves serve as a bearing for the end convolutions of the spring when they are contracted on opening the door, and thus prevent a binding of the spring against the pivotal pin, with a consequent wear and possible injury to the spring. One of the hinge plates has a pair of ears 18 cut therefrom and bent up with openings therethrough to receive the hook ends of a V-shaped bail wire 19, and the other hinge has a hook lug 20 cut therefrom and bent up to form a catch 20 to be engaged by the loop 19 for holding the spring plates in a fixed angular relation against the action of the spring 15. Both the ears 18 and the hook-shaped lug 20 lie in planes at right angles to the pivotal axis of the hinge, which insures their strength and rigidity.

The flanges 12 of the hinge plate 11 have engaging lugs 21 bent outwardly therefrom in substantially the same plane as the main portion of said hinge plate. A separate member or connecting plate 22 of substantially the same size and shape as the hinge plate 11 has upstanding flanges 23 at its ends corresponding with the upstanding flanges 12 of the hinge plate and fitting against the outer faces thereof, and these flanges 23 have shouldered recesses 24 to receive the lugs 21 and fit thereagainst. The hinge plate 11 has rearwardly projecting lugs 25 at its outer edges which engage the outer edges of the connecting plate 22. The connecting plate 22 is thus held between the lugs 21 and 25 of the hinge plate 11 and embraces the hinge between its end flanges 23.

The hinge plate 10 and the connecting plate 22 are provided with suitable openings for connecting screws 26 by means of which they may be attached respectively to the door and the door frame.

Assuming that the hinge plate 10 is connected with a door frame 27 and the connecting plate 22 is connected with the door 28, as shown, the spring 15 tends to keep the door closed as usual, but when it is desired to disconnect the door it is only necessary to open the door far enough to engage the loop 19 with the hook 20 and thus remove the spring pressure from the door, and then by swinging the door toward its closed position the hinge plate 11 being held by the loop has the connecting plate 22 stripped therefrom by first withdrawing it from engagement with the lugs 25 and then from the

lugs 21, the end flanges 23 thereof sliding freely from the end flanges 12 of the hinge as soon as the connecting plate is disengaged from the lugs 25. If the door is to be replaced by another door the latter is provided with connecting plates 22 and is mounted on the hinges by merely sliding the end flanges 23 along the end flanges of the hinge plates 11 until the shoulders of notches 24 engage the lugs 21. The door is then swung outwardly sufficient to bring the outer edge of the connecting plates 22 within the hooklike engagement of the lugs 25, and a still farther movement of the door in this direction causes the hinge plates 11 to swing and disengage the loops 19 from the hooks 20 so that when the door is released it will be swung closed by the hinge in the usual manner and the substitution of one door for another is complete without the removal of screws or any other loose part.

It is obviously immaterial whether the hinge plate 10 or the connecting plate 22 is connected to the door, though the former connection is preferable in the event of the door being replaced by another, as when screen doors and storm doors are interchangeable, as in such case it is only necessary to provide the doors with the connecting plates 22, of which there may be two provided for each hinge. When the removed door is not to be replaced by another, however, it may be preferred to position the connecting plates on the door jamb as being neater and offering less obstruction to the passage through the doorway when the door is removed. When, however, the spring plates 10 are attached to the door jamb and the door is removed without replacing it with another the hinge may be folded until the plates 10 and 11 are approximately parallel, in which position openings 29 in the end flanges 12 register with each other so that by dropping a headed pin or nail 30 therethrough the hinge parts are held in this folded position.

With the present construction the pivot pin 13 being mounted in turned-up flanges at the ends of the hinge plates 10 and 11 is allowed practically the full length thereof for receiving the spring 15, and consequently a spring of maximum length may be employed and the sleeves 17 at the ends of the spring prevent its binding and wearing on the pivot pin, and assure a freedom of action of the spring. The housing 14 also protects the spring from engagement with the clothes in the event of its becoming broken and also adds to the appearance of the device. Obviously a positive connection between the hinge plate 11 and the connecting plate 22 is required to maintain the hinge connected with the door when the spring has been broken, and for this purpose openings 31 are provided in the end flanges 23 of

the connecting plate, such openings registering with the openings 29 of the end flanges of the hinge plate 11 so that when the headed pin 30 is dropped therethrough, as shown in Fig. 6, it prevents the connecting plate from becoming disengaged from the hinge plate 11.

Another provision for locking the parts together when the spring breaks consists in the forming of an opening 32 in the hinge plate 11 registering with one of the screw openings of the connecting plate 22, so that when the spring breaks the screw may be removed from said opening and passed 15 through the registering openings of the plates 11 and 22 which will lock the parts together. The repair of a broken spring may be simply made as the hinge pin 13 is not upset at its ends but is free to be 20 driven out of the hinge members so that the broken spring may be removed from the rear of the spring housing and replaced with a new spring and the hinge pin returned, it being impossible for the hinge pin 25 to be lost when the hinge is in use, as the end flanges 23 of the connecting plate 22 fit against both ends thereof.

In mounting the hinge the connecting plate 22 serves as a guide as the shoulders 30 of the notches 24 thereof are so placed as to lie in the plane of the meeting edges of the door and its door jamb. This plate is placed against the door and moved toward the edge thereof until the shoulders of the 35 notches 24 engage a rule or other straight edge held against the edge of the door and projecting slightly beyond the face thereof. In this position of the plate the positions of the screws are marked through the screw 40 openings, and when the plate is attached the hinge is engaged therewith, and with the door in place and the loop 19 disengaged from the hook 20 the hinge plate 10 will be 45 in its proper position so that the positions of the screws may be marked through the screw openings thereof.

It is obvious that the rearwardly projecting engaging lugs 25 may be dispensed with by forming the notches 24 with hooklike 50 shoulders 24', as shown in Fig. 7, so that the opposite shoulders of the notches engage both sides of the lugs 21.

What I claim as new and desire to secure by Letters Patent is:

55 1. A detachable hinge, comprising a pair of hinge plates having their ends bent up to form end flanges in parallel planes at right angles to the plates, a hinge pin passing through the end flanges of the hinge plates to pivotally connect them together, lugs projecting from the ends of the hinge, a connecting plate having end flanges bent up therefrom to correspond with the end flanges of the hinge plates and embracing the end flanges of the hinge plates and pro-

vided with notches to receive the said projecting lugs, a spring tending to force the hinge plates apart, and means for holding the hinge plates against the action of the spring.

2. A detachable hinge, comprising a pair of hinge plates having their ends bent up to form end flanges in parallel planes at right angles to the hinge plates, said end flanges extending beyond the hinge plates and the 70 end flanges of one hinge plate fitting face to face against the outside of the end flanges of the other hinge plate, a hinge pin passing through the end flanges of the hinge plates, engaging lugs bent outwardly from the rear edges of the end flanges of the outer hinge plate, a connecting plate having end flanges bent up therefrom corresponding with the end flanges of the hinge plates and adapted to embrace the end flanges of the 75 outer hinge plate between them, the end flanges of the connecting plate having shouldered notches at their rear edges to receive the engaging lugs, a spring tending to force the hinge plates apart, and means for holding the hinge plates against the action of the spring.

3. A detachable hinge, comprising a pair of hinge plates having end flanges bent up therefrom in parallel planes at right angles thereto and extending beyond the inner edge of the hinge plates, the end flanges of one hinge plate fitting face to face against the outside of the end flanges of the other hinge plate, a hinge pin passing through the end flanges of the hinge plates for pivotally connecting them together, a spring housing 95 bent up from the inner edge of the inner hinge plate and closed at its ends by the end flanges thereof, a coil spring within the 100 spring housing surrounding the hinge pin with its ends engaging the respective hinge plates, engaging lugs at the ends of the hinge, a connecting plate adapted to fit behind the outer hinge plate and having end flanges to embrace the end flanges thereof, the end flanges of the connecting plate provided with notches to receive the connecting lugs, and means for holding the hinge plates 105 against the action of the spring.

4. A detachable hinge, comprising a pair of hinge plates having end flanges bent up therefrom in parallel planes at right angles thereto, a hinge pin passing loosely through the end flanges, bearing sleeves loosely mounted on the hinge pin and provided with flaring ends, a coil spring surrounding the hinge pin and engaging the bearing sleeves with its ends bearing against the respective hinge plates, a connecting plate having end flanges embracing the end flanges of the hinge plates and holding the hinge pin in place, locking means between one of the hinge plates and the connecting plate depending upon the spring action on 115 120 125 130

said hinge plate for locking them together, and means for holding the hinge plates against the action of the spring.

5. A detachable hinge, comprising hinge plates with end flanges bent therefrom in parallel planes at right angles thereto, the end flanges of the hinge plates being pivotally connected together, a spring acting on the respective hinge plates, a connecting 10 plate having end flanges bent up therefrom corresponding with the end flanges of the hinge plates and embracing the end flanges of the hinge plates between them, locking means between one of the hinge plates and the connecting plate depending upon the spring action on said hinge plate for locking them together, and means for holding the hinge plates against the action of the spring.
- 15 6. A detachable hinge, comprising hinge plates with end flanges bent therefrom in parallel planes at right angles thereto, the end flanges of the hinge plates being pivotally connected together, a spring acting on the respective hinge plates, a connecting 20 plate having end flanges bent up therefrom corresponding with the end flanges of the hinge plates and embracing the end flanges of the hinge plates between them, locking means between one of the hinge plates and the connecting plate depending upon the spring action on said hinge plate for locking them together, and means for holding the hinge plates against the action of the spring.
- 25 7. A detachable hinge, comprising hinge plates with end flanges bent therefrom in parallel planes at right angles thereto, the end flanges of the hinge plates being pivotally connected together, a spring acting on the respective hinge plates, a connecting 30 plate having end flanges bent up therefrom corresponding with the end flanges of the hinge plates and embracing the end flanges of the hinge plates between them, locking means between one of the hinge plates and the connecting plate depending upon the spring action of said hinge plate for locking them together, means for holding the hinge plates against the action of the spring,
- 35 8. A detachable hinge, comprising a pair of hinge plates having end flanges bent up therefrom in parallel planes at right angles thereto, the end flanges of the hinge plates being pivotally connected together with the end flanges of one hinge plate outside of the others, a spring acting on the respective hinge plates, engaging lugs bent outwardly from the rear edges of the 35 end flanges of the outer hinge plate, a connecting plate having end flanges bent up therefrom corresponding with the end flanges of the hinge plates and embracing the end flanges of the hinge plates between them, the end flanges of the connecting plate having shouldered notches at their rear edges to receive the engaging lugs, rearwardly extending engaging lugs on the outer edge of the outer hinge plate engaging the outer edge of the connecting plate, and means for holding the hinge plates against the action of the spring.
- 40 9. A detachable hinge, comprising hinge plates with end flanges bent therefrom in parallel planes at right angles thereto, the end flanges of the hinge plates being pivotally connected together, a spring acting

on the respective hinge plates, a connecting plate having end flanges bent up therefrom corresponding with the end flanges of the hinge plates and embracing the end flanges of the hinge plates between them, locking means between one of the hinge plates and the connecting plate depending upon the spring action of said hinge plates for locking them together, means for holding the hinge plates against the action of the spring, there being registering openings in the end flanges of the connecting plate and in the end flanges of one of the hinge plates, and a pin to fit in said registering openings to lock the hinge plates in engagement with the connecting plate.

8. A detachable hinge, comprising a pair of hinge plates having end flanges bent up therefrom in parallel planes at right angles thereto, the end flanges of the hinge plates being pivotally connected together with the end flanges of one hinge plate outside of the others, a spring acting on the respective hinge plates, engaging lugs bent outwardly from the rear edges of the 65 end flanges of the outer hinge plate, a connecting plate having end flanges bent up therefrom corresponding with the end flanges of the hinge plates and embracing the end flanges of the hinge plates between them, the end flanges of the connecting plate having shouldered notches at their rear edges to receive the engaging lugs, rearwardly extending engaging lugs on the outer edge of the outer hinge plate engaging the 70 outer edge of the connecting plate, and means for holding the hinge plates against the action of the spring.

In testimony whereof, I affix my signature, in presence of two witnesses.

WILLIAM R. TAYLOR.
